(57) **CLAIM**

The ornamental design for a shoe upper, as shown and described.

DESCRIPTION

FIG. 1 is a perspective view of the front, left and top of a shoe upper showing my new design;

FIG. 2 is a top plain elevational view thereof;

FIG. 3 is a left side view thereof;

FIG. 4 is a right side elevational view thereof;

FIG. 5 is a front elevational view thereof; and,

FIG. 6 is a rear elevational view.

The broken line showing the sole in the figures is for illustrative purposes only and forms no part of the claimed design.
